UNITED STATES PATENT OFFICE

2,066,601

VALVE GRINDING APPARATUS

Albert E. Wood, Battle Creek, Mich.

Application June 21, 1935, Serial No. 27,711

6 Claims. (Cl. 51—27)

My invention relates to valve grinding apparatus.

One of the objects of my invention is to provide an apparatus for grinding a valve having a flat face, on a flat seat, which will avoid the necessity for manual grinding of the valve. In grinding these flat valves, particularly in locomotive work, it may take a workman seven or eight hours to grind a single valve. This is very tiresome work and makes a job expensive. With my improved apparatus, the valve and seat may be placed in proper position with respect to the apparatus and the apparatus put into operation so that thereafter the attendant can simply leave the machine to do the work of grinding the valve and go on about other work.

Numerous other objects and advantages of the invention will be apparent from the description and claims.

20 In the drawing, in which apparatus embodying
my invention is illustrated:

Figure 1 is an end elevational view of the apparatus;

Fig. 2 is a side elevational view;

25 Fig. 3 is a section on the line 3—3 of Fig. 2;
Fig. 4 is a detail view of part of the control for
the valve lifting apparatus; and

Fig. 5 is a section on the line 5—5 of Fig. 2.

Referring to the drawing more in detail, the construction shown comprises a valve 1 having a flat face resting on a flat valve seat 2, apparatus for moving the valve back and forth on its seat and for periodically lifting it from its seat, comprising an oscillatable rock arm 3 provided with means for engaging the valve, and means for periodically lifting the rock arm comprising a second rock arm 4 on which the first rock arm is pivotally mounted at 5, cam means 6 for periodically actuating said second rock arm, a ratchet and pawl mechanism 7 for actuating the cam 6, having provision for periodically increasing the throw of the ratchet to effect a quick raising and lowering of the valve with respect to its seat, a motor 8 for driving the valve-moving and valve-lifting apparatus, and transmission from the motor to the rock arm 3 and the ratchet actuating pawl 9.

Before describing the construction in further detail, I will briefly outline the operation.

50 It is customary in grinding a valve of this type on its flat seat to provide an abrasive material between the valve and seat. In order to prevent this abrasive from becoming unevenly distributed between the faces of the valve and seat, it is
55 desirable to lift the valve from its seat occasion-

ally in order to effect a re-distribution of the abrasive.

In grinding the valve 1, the seat 2 is placed in proper position with respect to the apparatus, an abrasive is distributed over the face of the seat and the valve is placed on top of the seat. The valve, which has been drilled out to receive the pins 10 on the spring-pressed plungers 11, is connected with the rock arm 3 by turning the thumb buttons 12 on the ends of these plungers to a position in which the pins 13 on these buttons can enter the holes in the sides of the rock arm 3. The springs 14 then force these plungers 11 inwardly to cause the pins 10 on the ends of the plungers to enter the holes drilled in the sides of 15 the valve and to cause the plunger heads to enter between the vertical ribs 15 on the valve. The motor 8 is then put in operation to effect rotation of the crank or eccentric 16, causing a back and forth movement of the connecting rod or eccentric link 17 due to the engagement of the plunger 20 head between the ribs 15.

As shown in Figs. 2 and 5, one end of this connecting rod 17 is forked to straddle the upper end of the rock arm 3 and is provided with a guide and pivot pin 18, the ends of which are guided in horizontal slots 19 in the frame of the apparatus and the central portion of which extends through a T-shaped slot or opening 20 in the rock arm 3. When the rock arm 3 is in its lower position, as shown in Fig. 2, the pivot pin 18 is in the upper portion 21 of the T-shaped slot 20 so that back and forth movement of the connecting rod causes an oscillatory movement of the rock arm 3 and a shifting back and forth of the valve 1 over its seat 2 to effect the grinding operation. As the motor 8 continues to operate, the rotatable motor-driven cam member 6 presses downwardly on one end of the rock lever 4, lifting the other end of the rock lever 4 and hence lifting the rock arm 3. This lifting of the rock arm 3 lifts the valve 1 from its seat 2, due to the engagement of the pins 10 in the holes drilled in the valve. This lifting of the rock arm 3 is sufficient to free the pin 18 on the connecting rod from the upper portion 21 of the T-shaped slot and to cause it to enter the lower elongated slot portion 22. In this position the pin 18 on the connecting rod can reciprocate in the slot portion 22 without effecting any rocking movement of the rock arm 3. As the motor-driven cam 6 continues to rotate, it moves out of engagement with the end of the rock lever 4 and permits the rock arm 3 to drop down to its lower position again, in which the valve 1

will be in engagement with its seat 2 and the pin 18 on the connecting rod will be in the upper portion 21 of the T-shaped slot and will effect a reciprocation of the valve on its seat.

5 In order to move the rock arm 3 quickly from its lowermost to its uppermost position, means are provided, which will be described more in detail hereinafter, for effecting a relatively rapid rotation of the cam member 6 during a portion 10 of its revolution, this being effected in general by lengthening the effective stroke of the pawl 9 on the ratchet wheel 23 which operates the cam shaft 24.

This reciprocation of the valve on its seat 15 with the periodic lifting of the valve from its seat is continued until the valve is properly ground, the periodic lifting of the valve from its seat effecting a re-distribution of the abrasive.

I will now describe more in detail the construction.

The transmission from the motor 8 to the connecting rod 17 comprises a worm 25 on the motor shaft, a worm gear 26 driven from this worm, a shaft 27 on which the worm gear is mounted, a 25 spur pinion 28 mounted on this shaft, a spur gear 29 driven from the spur pinion 28, a second spur gear 30 driven from the first spur gear, a shaft 31 on which this second spur gear 30 is mounted, and the eccentric or crank 16 mounted on this 30 shaft 31 on which eccentric one end of the connecting rod 17 is journaled. The transmission from this connecting rod 17 to the ratchet wheel 23 is by means of a link 32 connected at 33 with the reciprocating end of the connecting rod 17, 35 a two-armed lever 34 pivotally mounted at 35 and having its upper end pivotally connected at 36 with the link 32, and the spring-pressed pawl 9 pivotally mounted at 37 on the lower end of the two-armed lever 34 and engaging the ratchet 40 wheel 23. As the end of the connecting rod 17 reciprocates, it will effect a back and forth movement of the pawl 9 which will effect a uni-directional rotation of the ratchet wheel 23, a non-return pawl 38 (Fig. 1) being provided to 45 prevent backward rotation of the ratchet wheel.

In order to effect the aforementioned change of speed of the ratchet wheel 23 for preventing the rock arm 3 from being held too long in its uppermost position, a horse-shoe shaped, rockably-mounted guard member 39 (Figs. 2 and 4) is provided which in one position holds the pawl 9 out of cooperative relation with respect to the ratchet wheel 23 during a substantial portion of the travel of the pawl and in another position 55 permits the pawl to engage the ratchet wheel during substantially the entire travel of the pawl. This horse-shoe shaped guard member is pivotally mounted at 35 on the frame and has its lower edge 40 extending into proximity to the 60 point of the pawl 9 so that in its lowermost position the point of the pawl is held out of engagement with the ratchet wheel except during the extreme latter portion of its feeding movement but so that in the raised position of the lower 65 arm of the horse-shoe the pawl will engage the ratchet wheel during substantially its entire movement. A coil torsion spring 41 is provided for the horse-shoe guard member which tends to hold the lower guard arm in its lowermost 70 position. In order to move this guard member to effect the long stroke action of the pawl, a cam member 42 is provided on the rotatable motor-driven shaft 24 which periodically engages a follower portion 43 on the upper arm of the horse- 75 shoe guard to move the guard to a position which

will enable the pawl to have a long, effective stroke.

This long effective stroke of the pawl takes place at a time when the cam 6 is effecting a lifting movement of the rock arm 3 so that this 5 rock arm is moved quickly from its lower grinding position to its upper resting position, thus bringing the rock arm 3 quickly to a position of rest by causing a spring positioning member 43a to engage a depression 43b in the upper end of 10 the arm 3. After the arm 3 has been raised to its upper position, the cam 42 passes out from under the follower 43, permitting the horse-shoe member 39 to drop and the short effective stroke 15 of the pawl to be resumed. The cam 6 then 15 travels along the arcuate portion 44 of the rock arm 4 for a time and then moves out of engagement with this arcuate follower, permitting the rock arm 3 to drop quickly to its lower operative position. I have found in practice that good 20 results are secured by designing the apparatus so that the valve will be held in its raised inoperative position for about eight seconds during each cycle and will be in its lower operative position for about forty seconds during each cycle. 25

In order to press the pawl into operative engagement with the ratchet wheel a coil compression spring 45 is provided seated in the pocket 30 of the frame of the apparatus and bearing upwardly on the pawl.

Any suitable securing means may be provided for holding the apparatus in position with respect to the work, such as the knurled nuts 46 threaded on the anchor studs 41.

By the use of this apparatus, it will be seen that the workmen can simply set up the valve and seat in proper position with respect to the apparatus, put the motor into operation, and leave the machine to do the work of grinding the valve. 40

Further modifications will be apparent to those skilled in the art and it is desired, therefore, that the invention be limited only by the prior art and the scope of the appended claims.

Having thus described my invention, what I claim and desire to secure by Letters Patent is:

1. Apparatus for grinding a valve having a flat face on a flat seat comprising reciprocable means for causing the flat face of the valve to move in a plane back and forth on its seat and means 50 cooperating with said reciprocable means for periodically separating the valve from its seat, said cooperating means comprising an oscillatable rock arm provided with means for engaging the valve and means for periodically lifting said rock arm, 55 said lifting means comprising a second rock arm on which said first rock arm is pivotally mounted.

2. Apparatus for grinding a valve having a flat face on a flat seat comprising reciprocable means for causing the flat face of the valve to move in a plane back and forth on its seat and means 60 cooperating with said reciprocable means for periodically separating the valve from its seat, said cooperating means comprising an oscillatable rock arm provided with means for engaging the 65 valve and means for periodically lifting said rock arm, said lifting means comprising a second rock arm on which said first rock arm is pivotally mounted and cam means for periodically actuating said second rock arm.

3. Apparatus for grinding a valve having a flat face on a flat seat comprising means for moving the valve back and forth on its seat and for periodically lifting it from its seat comprising an oscillatable rock arm provided with means for 70 75

engaging the valve, means for periodically lifting said rock arm, said lifting means comprising a second rock arm on which said first rock arm is pivotally mounted, cam means for periodically actuating said second rock arm, and a ratchet and pawl mechanism for actuating said cam.

4. Apparatus for grinding a valve having a flat face on a flat seat comprising means for moving the valve back and forth on its seat and for periodically lifting it from its seat comprising an oscillatable rock arm provided with means for engaging the valve, means for periodically lifting said rock arm, said lifting means comprising a second rock arm on which said first rock arm is pivotally mounted, cam means for periodically actuating said second rock arm, and a ratchet and pawl mechanism for actuating said cam, having provisions for periodically increasing the throw of the ratchet to effect a quick raising and lowering of the valve with respect to its seat.

5. Apparatus for grinding a valve having a flat face on a flat seat comprising reciprocable means for causing the flat face of the valve to move in a plane back and forth on its seat and means

cooperating with said reciprocable means for periodically separating the valve from its seat, said cooperating means comprising an oscillatable rock arm provided with means for engaging the valve and means for periodically lifting said rock arm, said lifting means comprising a second rock arm on which said first rock arm is pivotally mounted and rotary cam means for periodically actuating said second rock arm.

6. Apparatus for grinding a valve having a flat face on a flat seat comprising means for moving the valve back and forth on its seat and for periodically lifting it from its seat comprising an oscillatable rock arm provided with means for engaging the valve, means for periodically lifting said rock arm, said lifting means comprising a second rock arm on which said first rock arm is pivotally mounted, rotary cam means for periodically actuating said second rock arm, and means for periodically increasing the speed of the cam to effect a quick raising and lowering of the valve with respect to its seat.
